(57) CLAIM

The ornamental design for a lip patch, as shown and described.

DESCRIPTION

FIG. 1 is a perspective view of a lip patch embodying the design;

FIG. 2 is a front elevation view thereof;

FIG. 3 is a rear elevation view thereof;

FIG. 4 is a left side view thereof;

FIG. 5 is a right side view thereof;

FIG. 6 is a top view thereof;

FIG. 7 is a bottom view thereof; and,

FIG. 8 illustrates the lip patch in one form of use.

The broken lines in FIG. 8 form no part of the design.
